US0D1005732S

(12) **United States Design Patent** (10) **Patent No.:** **US D1,005,732 S**
(45) **Date of Patent:** **** Nov. 28, 2023**

(54) **DISPLAY SHELF**

(71) Applicant: **Displays by Martin Paul, Inc.—Creative Center**, Denton, TX (US)

(72) Inventor: **Martin Belokin**, Denton, TX (US)

(73) Assignee: **Displays by Martin Paul, Inc.—Creative Center**, Denton, TX (US)

(**) Term: **15 Years**

(21) Appl. No.: **29/725,161**

(22) Filed: **Feb. 21, 2020**

(51) **LOC (14) Cl.** **08-08**

(52) **U.S. Cl.**

USPC **D6/569**

(58) **Field of Classification Search**

(57) **CLAIM**

The ornamental design for the display shelf, as shown and described.

DESCRIPTION

FIG. 1 is a front perspective view of the design; FIG. 2 is a front view of the design of FIG. 1; FIG. 3 is a back view of the design of FIG. 1; FIG. 4 is a left side view of the design of FIG. 1; FIG. 5 is a right side view of the design of FIG. 1; FIG. 6 is a top view of the design of FIG. 1; FIG. 7 is a bottom view of the design of FIG. 1; and, FIG. 8 is a rear perspective view of the design of FIG. 1. The dashed lines in the FIGURES represent a lip that can be used in conjunction with the design; however, they for no part of the claimed design.

1 Claim, 6 Drawing Sheets
